UNITED STATES PATENT OFFICE.

CHARLES W. WESTON, OF PAMPA, TEXAS, ASSIGNOR OF ONE-FOURTH TO ZACK WILSON, OF HIDALGO COUNTY, TEXAS, AND ONE-HALF TO F. E. OSBORN, F. B. FREELAND, AND GORDON GRIFFIN, ALL OF McALLEN, TEXAS.

DESIGN FOR A SERVING COUNTER.

Application filed June 13, 1927. Serial No. 22,412. Term of patent 3½ years.

To all whom it may concern:

Be it known that I, CHARLES W. WESTON, a citizen of the United States, residing at Pampa, in the county of Gray and State of Texas, have invented a new, original, and ornamental Design for a Serving Counter, of which the following is a specification, reference being had to the accompanying drawing, forming a part thereof.

I claim: The ornamental design for a serving counter, as shown.

CHARLES W. WESTON.
